(57) **CLAIM**

The ornamental design for a sphygmomanometer, as shown and described.

DESCRIPTION

FIG. 1 is a front, bottom, and right side perspective view taken from a first view angle of a sphygmomanometer showing our new design;

FIG. 2 is a front, bottom, and right side perspective view taken from a second view angle thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines shown in the figures illustrate portions of the sphygmomanometer that form no part of the claimed design.
